MOUNTING AND OPERATING MEANS FOR
VENETIAN BLINDS

Arthur Cusick, Youngstown, Ohio

Application March 8, 1947, Serial No. 733,330

4 Claims. (Cl. 160—168)

1

This invention relates to Venetian blinds and more particularly to mounting and operating means therefor.

The principal object of the invention is the provision of novel means of mounting and operating Venetian blinds.

A further object of the invention is the provision of a Venetian blind construction, the slat portions of which are unobstructed by tapes or ropes throughout their entire effective length.

A still further object of the invention is the provision of a Venetian blind including a plurality of slats positioned in detachable relation to operating means disposed adjacent their end portions.

A still further object of the invention is the provision of a simple and inexpensive method of mounting Venetian blind slats.

The present invention relates to Venetian blinds in which a plurality of slats of suitable material such as thin steel or aluminum are provided with transverse curves and positioned in front of a window and arranged so that the slats may be tilted to various angles so as to control the amount of light admitted through the window. In the present invention the Venetian blind disclosed includes a tilting structure and a number of slats which are unencumbered throughout their length and thereby avoid the heretofore believed necessary mounting tapes and ropes which are objectionable from a point of view of appearance and cleanliness.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention is illustrated in the accompanying drawing, wherein—

Figure 1 is a perspective view of a portion of a Venetian blind formed in accordance with the invention.

Figure 2 is a top plan view of a portion of a slat of a Venetian blind.

Figure 3 is a cross section of a portion of the Venetian blind slat and mounting means shown in Figure 2.

Figure 4 is an end elevation of a portion of the mounting means of the slat shown in Figure 2 and taken on line 4—4 of Figure 2.

2

Figure 5 is a cross section of a portion of a mounting means of the Venetian blind slat shown in Figure 2 and taken on line 5—5 thereof.

Figure 6 is an alternate form of mounting means for a Venetian blind slat.

Figure 7 is a plan view of the alternate mounting means shown in Figure 6.

By referring to the drawings and Figure 1 in particular it will be seen that a portion of a Venetian blind has been disclosed and includes a tilt board 10, a supporting rope 11 and a pair of flexible (preferably fabric) tapes 12 and 13 affixed to the end of the tilt board 10 as by means of eyelets 14 and 15 formed in the tapes 12 and 13, respectively, and engaged over head members 16 and 17 positioned on the end of the tilt board 10 and projecting therefrom. The tapes 12 and 13 depend from the head members 16 and 17 and are provided with additional eyelets 14 and 15 at regularly spaced intervals and are adapted to carry a plurality of Venetian blind slats 18 arranged in spaced relation below the tilt board 10.

Each of the slats 18, which are preferably formed of thin metal and transversely bowed as shown, is provided at their ends with a pair of clips 19 which in turn carry head members 20 engageable with the eyelets 14 and 15 in the tapes 12 and 13, thus providing for the support of the slats 18 by the tapes 12 and 13 which are in turn carried by the tilt board 10. The head members 20 and the eyelets 14 and 15 are so arranged that the head members 20 may revolve relatively freely in the eyelets 14 and at the same time be retained therein until forcibly removed therefrom.

By referring to Figures 2, 3, 4 and 5 of the drawings, detailed views of the clips 19, the head members 20 and the eyelets 14 and 15 may be seen. It will be observed that the eyelets 14 and 15 are preferably formed, as best shown in Figures 4 and 5, with spring members 21 therein so that when the head members 20 are passed therethrough, the spring members 21 will expand to receive the same and then contract to hold the same in position.

In Figures 4 and 5 of the drawings the vertical height of the eyelet members 14 is exaggerated as it will be understood that they are normally formed with as little vertical height as possible so as to facilitate the stacking of the vertical slats 18 when the same are pulled upwardly as by means of the ropes 11.

By referring again to Figure 1 of the drawings it will be seen that each of the slats 18 is provided with a T-shaped opening 9 formed in each

end thereof and providing a vertical channel through which the ropes 11 are normally positioned. It will thus be seen that in assembling the Venetian blind as disclosed herein, the tapes 12 and 13 are attached at their uppermost ends to the tilt board 10 of the Venetian blind mechanism which is usually mounted so that it can be tilted transversely and thereby control the angle of the several slats 18 appended thereto. The slats 18 are each mounted on the tapes 12 and 13 by the registering of the head members 20 with the eyelets 14 and 15, respectively, and the ropes or cords 11 positioned through the assembly so that the entire assembly of slats 18 may be moved upwardly thereby as in raising the entire blind. Normally, light is controlled by the blind by tilting the tilt board 10 in a manner known in the art and thereby causing the tape 12, for example, to rise while the tape 13 descends and thus imparts tilting motion to each of the slats 18 secured thereto. It will thus be seen that the engagement between the head members 20 of the clips 19 and the eyelets 14 and 15 must be loose enough so that the tapes 12 and 13 in which the eyelets 14 and 15 are located will not be twisted out of vertical alignment.

By referring to Figures 1, 2 and 3 of the drawings it will be seen that each of the clips 19 is preferably affixed to the ends of the slats 18 by dimpling the same as indicated by the numerals 22 in the several figures of the drawings. In Figure 3 of the drawings, in which a vertical cross section is shown, it will be seen that the dimpling 22 may be preformed in the end of the slat 18 and preformed in the clip 19 so that the dimpling 22 may be brought into registry when the clip 19 is applied thereto, or the dimpling 22 may be impressed through the clip 19 and the slat 18 when the clip 19 is installed thereon.

It will be obvious to those skilled in the art that several variations in the form of clips 19 and/or the eyelets 14 and 15 may be used without departing from the spirit of the invention and in Figures 6 and 7 one such alternate form of clip is shown. In Figures 6 and 7 of the drawings a portion of a Venetian blind slat 23 is shown and a modified form of clip 24 is shown attached thereto. The clip 24 is in the form of a semi-U-shaped member, the arms of which are closely spaced with respect to one another. The arms are indicated by the numerals 25 and 26. One of the arms is provided with an indentation 27 adapted to register with the outermost end of the slat 23 and the opposite arm is formed with a downturned section 28 adapted to register with an opening 29 in the slat 23. This form of clip is self-retaining on the blind slat 23 and has the additional feature of providing a spring action in the looped head portion thereof which may be engaged directly in an eyelet with a spring action retaining characteristic depending upon the loop formation of the clip 24.

It will thus be seen that a Venetian blind may be formed by using the herein disclosed means of mounting the several slats on the ends thereof so that the blind is entirely free of obstructing tapes such as are commonly used in Venetian blind structures. It will also be seen that the slats of the blind can be readily removed for cleaning purposes. The construction disclosed is simple, inexpensive in manufacture and lends itself to relatively quick and easy Venetian blind construction and assembly. It will thus be seen

that the several objects of the invention are met by the structures disclosed.

Having thus described my invention, what I claim is:

- 5 1. In a Venetian blind including a tilting mechanism and a plurality of slats, means for suspending the slats in operative relation from the said tilting mechanism, said means including clips affixed to the ends of the said slats, projecting head members formed on the said clips and pairs of fabric tapes depending from the said tilting mechanism, eyelets formed in the said tapes, and springs in said eyelets partially restricting the same, the head members of the clips 10 engaging the said eyelets so as to distort the 15 springs and be retained therein and so as to suspend the slats from the said tapes.
- 20 2. Means for supporting thin metal Venetian blind slats by their outermost ends, said means including pairs of vertically positioned flexible support members having spaced openings formed therein, spring clips on said members registering with said openings, members attachable to the ends of the said Venetian blind slats and having headed projections formed thereon and normally 25 in registry with the said spaced openings and retained by the said spring clips whereby movement imparted to the supporting members is transmitted to the slats for tilting the same.
- 30 3. A Venetian blind including a tilting member, a plurality of slats disposed therebeneath, pairs of tapes pivotally affixed to the ends of the tilting member and suspended therefrom, eyelets having tensioning springs therein formed in spaced relation in the said tapes, pairs of clips 35 positioned on each end of each of the said slats in spaced relation to one another, headed projections on the said clips disengageably secured in the said eyelets and normally retained therein 40 by said springs, the said headed projections being rotatable in the said eyelets when the tilting mechanism is tilted and the movement imparted to the several slats through the said tapes.
- 45 4. A Venetian blind including a tilting member, a plurality of slats disposed therebeneath, pairs of tapes pivotally affixed to the ends of the tilting member and suspended therefrom, eyelets formed in spaced relation in the said tapes, spring clips on said eyelets, pairs of clips positioned on each end of each of the said slats in spaced relation to one another, headed projections on the said clips disengageably positioned in the said eyelets, and secured by said spring 50 clips, the said projections being rotatable in the said eyelets when the tilting mechanism is tilted and the movement imparted to the several slats through the said tapes, dimples formed in the said slats and in each of the said clips, the said clips normally being in registry with the dimpled areas of the said slats so as to be self-retaining thereon.

ARTHUR CUSICK.
